UNITED STATES PATENT OFFICE.

AUGUST VON PARSEVAL, OF AUGSBURG, GERMANY, ASSIGNOR TO MOTORLUFTSCHIFF-STUDIENGESELLSCHAFT M. B. H., OF BERLIN, GERMANY.

CAR SUSPENSION FOR MOTOR-BALLOONS.

No. 872,539.

Specification of Letters Patent.

Patented Dec. 3, 1907.

Application filed June 30, 1906. Serial No. 324,228.

To all whom it may concern:

Be it known that I, AUGUST VON PARSEVAL, a subject of the German Emperor, and resident of Augsburg, Germany, have invented 5 certain new and useful Improvements in Car Suspensions for Motor-Balloons, of which the following is a specification.

This invention relates to motor balloons and especially to motor balloon-suspensions 10 its object being to provide a suspension of this kind which would be very simple in construction and very efficient in use.

In the annexed drawings: Figure 1 is a side elevation view of a balloon the car of 15 which is suspended according to the present invention. Fig. 2 is a front elevation of same.

The new suspension comprises the well known parallel pairs of cables 1 and 2 which 20 have the same length and rigidly connect the middle part of the balloon with the car, as well as the oblique ropes 3 and 4, which supports the projecting points of the balloon and pass at the car under gliding rollers 25 5 and 6.

When the car oscillates it follows circular courses at the ends of the ropes 1 and 2 while sliding by means of the rollers 5 and 6 on the sliding ropes.

30 In order to prevent of the axis of the balloon being deformed by the sliding ropes the dimensions of the ropes are calculated in such a manner that the circular motion of the points 7 and 8 coincides within the limits 35 9 and 10 of the motion of the car which are practically to be considered, with that part of the elliptical way which corresponds to the motion of the slide ropes. The focuses of the ellipsis are at 11 and 12.

40 The advantages of this suspension are the following:

1.—A long and rigid supporting framework for the car is not necessary.

2.—The screw propeller may be located 45 between the balloon and the car so that it is best protected against damage when landing.

3.—Owing to the large distance between the motor and the balloon any danger of explosion is excluded.

50 4.—The upwardly directed tilting moment

of the low placed propeller screw is strongly diminished as under the pressure of the propeller screw the car automatically advances and carries its center of gravity ahead.

5.—Owing to this advancing and following 55 motion of the car the pitching motions of the balloon produced by the variation of the speed are considerably reduced.

Consequently in spite of the low position of the car dynamic effects are obtained as if 60 the car be suspended very high *i. e.* at the height of the securing points 13 and 14 of the parallel ropes.

The above described car suspension consequently unites the advantages of a low position 65 of the car with that of a highly positioned center of gravity of the car.

The arrangement may also be used as a rigid suspension if it is desired to control the inclined position of the balloon by shifting 70 the center of gravity of the car. In this case the car may be held in the desired position by the sliding ropes themselves, by connecting the latter with a roller 15 in such a manner that the rope is prevented from slipping on 75 the roller. The mechanical rotation of this roller produces the shifting of the car.

Having now fully described my said invention what I claim and desire to secure by 80 Letters Patent is:

1. In combination, a balloon, a car, flexible supporting ropes connecting the car with the balloon, and flexible guiding ropes secured to the balloon and slidably engaged with the car to permit movement of the 85 same, the guiding ropes being so arranged with respect to the supporting ropes and the two sets of ropes being so proportioned that both are maintained taut by the weight of the car in any position which the same may 90 assume.

2. In combination, a balloon, a car, flexible supporting ropes connecting the car with the balloon and permitting movement of the car, rollers for the car, and flexible guide 95 ropes longitudinally disposed with respect to the axis of the balloon and connected therewith, said ropes passing beneath said rollers, said supporting and guide ropes being so proportioned and disposed with respect to each 100

other that the weight of the car maintains said ropes taut in any position which it may assume.

3. In combination, a balloon, a car, flexible means for supporting the car from the balloon in a manner to permit movement of the car, and flexible guiding means connected with the balloon and slidably connected with the car to guide the same in its changing positions, said guiding and supporting means

being so proportioned and so disposed with respect to each other as to distribute the weight of the car equally thereon.

In testimony whereof I have hereunto set my hand, in presence of two witnesses.

AUGUST VON PARSEVAL.
